[57] CLAIM

The ornamental design for a combined toothpaste dispenser and toothbrush holder, as shown and described.

DESCRIPTION

FIG. 1 is a front elevational view of the combined toothpaste dispenser and toothbrush holder of the present invention; FIG. 2 is a left side elevational view of the combined toothpaste dispenser and toothbrush holder of FIG. 1, the right side elevational view being a mirror image thereof; FIG. 3 is a top plan view of the combined toothpaste dispenser and toothbrush holder of FIG. 1; and, FIG. 4 is a bottom plan view of the combined toothpaste dispenser and toothbrush holder of FIG. 1.

The rear of the combined toothpaste dispenser and toothbrush holder is flat and unornamented.
